CHARLES H. HERSEY AND WALTER E. HAWES, OF BOSTON, MASSACHUSETTS,
ASSIGNORS TO THEMSELVES AND F. C. HERSEY, OF SAME PLACE.

Letters Patent No. 91,132, dated June 8, 1869.

IMPROVED GLASS-WARE PRESS.

The Schedule referred to in these Letters Patent and making part of the same.

To all whom it may concern:

Be it known that we, CHARLES H. HERSEY and WALTER E. HAWES, both of Boston, in the county of Suffolk, and State of Massachusetts, have invented an Improved Glass-Ware Press; and we do hereby declare that the following, taken in connection with the drawings which accompany and form part of this specification, is a description of our invention, sufficient to enable those skilled in the art to practise it.

In glass-ware presses, it is desirable to have the construction such that the movement of the platen, or presser toward the bed shall begin with a rapid motion, and shall terminate with a slow, but powerful movement, and it is also desirable that this movement shall be effected by means which will operate with so little friction and side-thrust that the press will work sensitively, or so that the operator can determine, by feeling, the resistance offered just when the pressing-operation and movement should be discontinued.

Glass-ware presses have been devised, and are in operation, by which the force applied produces, at first, a quick, but not powerful movement, which gradually changes to a slow, powerful movement, completing the pressure under which glass-ware is formed in moulds; but in such presses, by reason of the introduction of gears, and other peculiarities of construction and arrangement, so much power is absorbed in friction, and in overcoming side-strains, and in changing the direction of motion, that the operator cannot feel, through the lever, when the plunger of the glass-ware mould has displaced the molten glass, so as to cause it to fill all the vacant space in the mould.

If pressure is continued on the mould after the space therein is filled with the molten, or hot, plastic glass, the result, as the glass is practicably incompressible, is to strain, and otherwise rapidly injure the mould, and also the quality of the glass-ware produced therefrom, such excess of pressure giving to the glass-ware a crystalline formation.

Our invention consists in the peculiar combination and arrangement of the parts, substantially as described, by which the moving-parts operate to give the platen, or presser a motion which changes from a rapid one, with small force, to a slow, powerful movement, while leaving the press delicate and sensitive in its indication, through the lever, of the resistance offered to continued pressing-movement.

Figure 1, of the drawings, shows, in front elevation, and

Figure 2, in side elevation, a glass-ware press embodying our invention, the parts being shown in the position which they have previous to making a stroke or giving an impression, though in fig. 2 is shown, in red lines, the position of the parts when the platen, or presser is brought to its lowest position in making an impression.

To the bed *a*, suitably supported at a convenient height, are attached, one on each side, two uprights, *b*, in the top and bottom ends of each of which are formed guide-ways, in which the ends of the cross-head *c* and cross-tail *d* can be made to reciprocate simultaneously, they being connected by links *e*.

Toggles, made by the links *f* and *g*, on each side of the machine, are operated by movement of the rocker-lever *h*, connected to the toggles by the links *i*. Each link *f* of each toggle is pivoted to a fixed pivot in each upright, *b*, and the lower link, *g*, of each toggle is connected to the cross-tail *d*.

The rocker-lever *h* is fixed upon the rocker-shaft *k*, which carries, at one end, a rocker-arm, *l*, one link *i* being coupled to the rocker-lever *h*, and the other link *i* being coupled to the rocker-arm *l*, said links being connected, one to each toggle.

On the inner surfaces of the uprights *b* are guide-ways *m*, which guide the reciprocations given to the platen, or presser *n*, this being connected to the cross-head *c* by the screw *o* and nuts *p*, by which the platen can be adjusted toward and from the bed, to suit various heights of moulds.

To counterbalance the gravitation of the moving-parts, and thereby increase the sensitiveness of the press, cords or chains *q*, having suitable weights *r* at one end, pass over wheels or pulleys *s*, and are attached to the cross-head *c*.

It will be obvious that the first part of the movement of the lever toward and by the operator will, at first, rapidly move the platen by straightening the toggles, and that the movement of the platen, proportionately to the movement of the lever, will grow less and less in distance, and more and more powerful in effect as the toggles approach a straight line.

It is at the time when the toggles approach a straight line in the plane which passes through the axes of the links *e*, that the resistance to further movement of the platen is opposed by the filling of the space in the mould completely with glass. At this time, particularly, the operator can feel the resistance which indicates to him that he should cease to strain on the lever, for, owing to the position of the toggles, which thrust directly down on the cross-tail which pulls through the links *e* in a direct line with

the cross-head, there are no side-thrusts and strains to create frictional resistance, which, as in weighing-apparatus, is reduced to a minimum on a system of pivots, or centres.

When the operator feels, by the resistance of the glass, that the pressing-operation has been brought to a point beyond which continuance would be injurious, he throws the lever back to its vertical position, the counterbalancing weights facilitating that and the rise of the platen.

On an extension of the rocker-shaft *k*, preferably at the end opposite that to which the lever *h* is at-

tached, an arm may be fixed, for the purpose of carrying an adjustable counterpoise.

We claim, in a glass-ware press, the combination, with the cross-head, to which the platen is connected, of the links *e*, cross-tail *d*, toggles *f g*, links *i*, and the rocker-lever, shaft, and arm, arranged and operating as herein described.

CHAS. H. HERSEY.
WALTER E. HAWES.
